UNITED STATES PATENT OFFICE

ORRICK JOHNS, OF SAPPINGTON, MISSOURI

DESIGN FOR A CRUTCH

Application filed July 30, 1930. Serial No. 36,518. Term of patent 14 years.

To all whom it may concern:

Be it known that I, ORRICK JOHNS, a citizen of the United States, residing at Sappington, county of St. Louis, State of Missouri, have invented a certain new, original, and ornamental Design for a Crutch, of which the following is a specification, reference being made to the accompanying draw-

ing, forming a part thereof, of which Fig. 1 illustrates in front perspective, and Fig. 2 illustrates in side elevation a crutch embodying my new design.

I claim—

The ornamental design for a crutch substantially as shown.

ORRICK JOHNS.
